UNITED STATES PATENT OFFICE

2,232,031

ASH AND DRIP RECEIVER

Peter Kavanagh, Liverpool, England

Application April 14, 1938, Serial No. 202,112
In Great Britain April 15, 1937

4 Claims. (Cl. 131—238)

The aim of this invention is to provide efficient and convenient means combined with a table, or like surface, for the reception or collection of tobacco ash and/or liquid drippings, being particularly suitable for use in dining and refreshment rooms of ships, railway trains, hotels, and such-like places; and has for its primary object to eliminate unauthorised removal of ash-receiving receptacles placed for public use on tables, or like surfaces. A further object of my invention resides in the protection of the table, or like surface, from disfigurement by contact with lighted cigarette ends or by rough usage, thus maintaining the table in good condition and appearance.

According to my invention, I provide a table, or like surface, having an aperture or apertures formed therein, a supported tobacco ash and/or drip receiving bowl or like receptacle, removably located within or under the or each of said aperture or apertures and so that its open top is situated below said table or like surface, a grid-like member fitted within the or each surface aperture and covering said bowl, and normally concealed retaining means whereby said grid-like member and said bowl are locked to prevent or render difficult their unauthorised removal.

One form of my invention comprises a table-like surface tiltably mounted—upon the release of a normally concealed locking catch—about a pivot or hinge connecting the table-like surface with a support, an aperture formed in said surface, a bowl or receptacle carried by said support and located within or under said aperture and so that the open end of the bowl or receptacle lies below the same, and a grid-like member fitted within said aperture and flush with the table-like surface so as to cover the bowl or receptacle; the grid-like member and bowl being located in such manner as to render difficult unauthorised removal thereof.

Another form of my invention comprises a table-like surface, an aperture formed in said surface, a bowl or receptacle located within or under said aperture and so that its upper open end lies below the same, a frame fitted upon said table-like surface and which consists of an inner ring-like or equivalent member provided with a ledge situated within the upper end of said aperture and a series of radially arranged arms extending outwardly from said inner ring-like or equivalent member over the upper face of the table-like surface and merging into an outer flat ring or flange which is downwardly curved or bent so as to follow the contour of the outer corresponding edge or periphery of the table-like

surface, and a grid-like member fitted upon said ledge so as to cover said bowl or receptacle; the grid-like member and bowl being located in such manner as to render difficult unauthorised removal thereof.

Each of said radially spaced arms may be provided with a groove or channel which extends towards and crosses said inner ring-like member in order to conduct drips to the bowl or receptacle situated below said ring-like member.

I will further describe my invention with the aid of the accompanying sheets of explanatory drawings which illustrate, by way of example only, one mode of carrying my invention into effect.

In said drawings—

Fig. 1 is a longitudinal sectional elevation of a table combined with my improvements, and

Fig. 2 is a corresponding plan view but with the grid-like cover of the ash and drip-receiving or collecting receptacle removed.

Figs. 3 and 4 are detail views in plan and side elevation, respectively, of the grid-like cover.

Fig. 5 is a fragmentary sectional elevation showing an alternative mode of anchoring the base or foot of the table to a concrete or cement floor.

Fig. 6 is a plan view illustrating the key-way in the floor bearing of Fig. 1.

In the several views like characters of reference denote like or equivalent parts wherever they occur.

Referring now to the drawings, to the upper surface of a wooden base or top board *a* of the table there is fitted a metal frame member which includes an inner ring-like member *b* having a circular ledge *b*¹—see Fig. 2—and an outer peripheral flat ring-like member or flange *b*² which is downwardly curved at *b*³ so as to follow the contour of and shield the outer or corresponding edge—which in this example is circular—of base board *a*. Extending outwardly from the inner ring *b*, across the upper surface of the base board *a*, are a series of radially arranged and equidistantly spaced arms *b*⁴ which merge into said outer flat ring *b*². In the example illustrated the radial arms are set at 90° apart.

Resting upon ledge *b*¹ of inner ring member *b* is a correspondingly shaped grid-like cover *c* of metal, porcelain, or other suitable material having apertures *c*¹ of any suitable design which may be arranged to spell a desired advertisement, and a peripheral shoulder *c*² which engages with ledge *b*¹ so as to permit the cover *c* to lie flush within the ring *b*. A series of recesses *c*³ are formed in

the periphery of cover *c* to receive correspondingly shaped locating projections *b*⁵ which extend inwardly from ring *b*. The grid-like cover *c* is retained in position—so as to render difficult its unauthorised removal—by means of a pin *d* projecting from one side of cover *c* and engaging in a corresponding socket *e* in ring *b*, and a spring-loaded ball or plunger *f* located diametrically opposite to socket *e* in ring *b* and engaging in a corresponding recess *g* in the adjacent side of cover *c*. It will be appreciated that the locking arrangement for cover *c* is normally concealed from view.

The inner ring member *b* seats within the upper end of a central aperture *a*¹ provided in the base board *a*, whilst the outer ring-like member *b*² and arms *b*⁴ of the metal frame are cast with a series of bosses *h* which project from the underside of the metal frame and are located in corresponding dowel apertures *a*² provided in upper face of base board *a*. The metal frame is securely fastened to the top surface of base board *a* by means of screws *j* entered upwardly through base board *a* and engaging within corresponding screw-tapped passages in said boss projections *h*.

A circular collar *k*¹ extending upwardly from a casting *k* located at the top of the table leg support or column *l*, is located within the central aperture *a*¹ of base board *a*, whilst disposed below the adjacent inner ring *b* is an outwardly extending top flange *m*¹ of a bowl or receptacle *m* which is situated under the upper surface of the table, being suspended below the grid-like cover *c* by means of its flange *m*¹ resting upon the upper end of the collar *k*¹ of casting *k*.

Secured to the underside of the base board *a* is a square wooden block *n* which has a central aperture for the passage of the collar *k*¹, and which block *n*, is hinged at *o* to an outwardly projecting flange *k*² of casting *k*, whilst the other side of the block *n* is provided with a normally concealed spring-returned locking catch or bolt *p* which, when pulled outwardly to released position, permits the table top structure, which comprises the metal frame *b*, *b*², *b*⁴, grid-like cover *c* and under block *n*, to be tilted about its hinged connection *o* in order to permit removal of the bowl *m* for cleaning purposes. It will thus be seen that unauthorized removal of the bowl is frustrated.

Extending downwardly from flange *k*² of casting *k* are arms *k*³ which curve inwardly to terminate in a boss *k*⁴ having an internally screw-tapped passage which engages with a screw-threaded rod end *l*¹ of the supporting column *l*, whereby casting *k* is secured thereto. Also screwed on said rod end *l*¹ is a circular flange member *l*² which abuts against a shoulder *l*³ of column *l*, whilst resting on said circular flange *l*² is a circular under-table *q* for the reception of parcels, hats, or the like.

In assembling the table, the circular flange *l*² is screwed down the rod end *l*¹ until it abuts against the shoulder *l*³, then the under-table *q* is placed over the rod end *l*¹ to seat upon the flange *l*², and finally the upper casting *k* is screwed onto the upper end of rod *l*¹; in this manner the under-table *q* and casting *k* are securely positioned on column *l*.

The supporting column *l* is hollow, and disposed within a recessed part *l*⁴ of an intermediate ornamental portion *l*⁵ is a press-button *r* of an electric bell whereto are connected current conductors *r*¹ which extend downwardly within the hollow interior of column *l* and pass through a

central aperture *l*⁶ in a bottom spindle end *l*⁷ of column *l*, to be connected with contacts *l*⁸.

The spindle end *l*⁷ of supporting column *l* passes through a bearing *s* located in floor boards *t*, said bearing being secured by bolts *u* which engage with an outward flange *s*¹ of bearing *s* and a securing plate *v*. The upper end of the bearing *s* is provided with a bevelled recess *s*² which receives and retains a corresponding apertured edge of a floor covering *t*. The floor bearing *s* is provided with a key-way *s*³ for the passage of key projections *l*⁹ provided at the lower end of spindle *l*⁷, whilst the bearing *s* is also formed with opposed cam faces *s*⁴ so that when the table column *l* is rotated in one direction or the other said cam faces co-act with the key projections *l*⁹ to secure the table to the floor.

Non-removably fitted near the lower end of the supporting column *l* are a pair of oppositely disposed metal bowls *w* which may be used as foot rests, ash trays, or refuse holders.

Preferably, each space existing between the adjacent arms *b*⁴ of the metal frame *b*, *b*², *b*⁴ is filled in by a correspondingly shaped piece or section of glass, rubber, or any other suitable surface 25 of hard wearing or non-inflammable material designated *x* which has its perimeter bevelled at *x*¹ and held in position by corresponding bevelled edges *b*⁶ of the surrounding members of the metal frame *b*, *b*², *b*⁴, in such manner as to be flush 30 with the upper surface of the latter.

Each arm *b*⁴ of the metal frame *b*, *b*², *b*⁴ is provided with a groove or channel *b*⁷ which extends towards and crosses the inner ring member *b* in order to conduct drips to the central bowl *m*—35 which may also constitute a container for cigarette ash—whilst the outer edges of said arms *b*⁴ where they merge into the flat ring *b*² may be provided with recesses *b*⁸ which constitute cigarette rests. The bowl *m* may be partially filled 40 with water to extinguish lighted cigarette ends which may be entered through the apertures *c*¹ of cover *c*.

The cover *c* is provided with grooves or channels *c*⁴ which register with the grooves *b*⁷ of the radial arms *b*⁴ in order to facilitate the passage 45 of the drips through the openings *c*¹ in cover *c*.

The underside of base board *a* may be provided with an ornamental beading *y* held in position by wood-screws.

The table top *a* and so the metal arms *b*⁴ may have a slight slope towards the central bowl *m* in order to enhance the passage of drips thereto, but the table top may, of course, be perfectly flat.

In an alternative mode of anchoring the base or foot of the table to a concrete or cement floor as illustrated in Fig. 5, a floor bearing *s* having a keyway *s*³ is embedded in the concrete, whilst the key projections *l*⁹ at the lower end of the spindle *l*⁷ coact with the cam faces *s*⁴ of bearing *s* in such manner that when the table is rotated in one direction or the other, the key projections *l*⁹ bind against the cam surfaces *s*⁴, as previously described with reference to Fig. 1.

Apertures *z* are provided in the floor bearings *s* of Fig. 1 and Fig. 5 for the reception of a connecting plug, or the like, from the source of electricity supply to connect with the contacts *l*⁸.

The present invention is capable of considerable modification and such changes thereto as come within the scope of the appended claims are deemed to be a part of my invention.

What I claim as my invention and desire to secure by Letters Patent is:

1. An improvement in tables comprising a sup- 75

- port, a table top tiltably mounted upon said support, an aperture formed in said top, a receptacle carried by said support and located within said aperture with the open end of the receptacle lying below the top thereof, a grid-like member, concealed means detachably connecting said grid-like member within said aperture for covering said receptacle and normally concealed retaining means locking said top upon said support.
- 5 10 2. An improvement in tables comprising a supporting surface, an aperture formed in said surface, a receptacle located within said aperture with the upper open end thereof lying below the surface of said top, a frame fitted upon said top consisting of an inner rim-like member provided with a ledge situated within the upper end of said aperture and a series of radially arranged arms extending outwardly from said inner rim-like
- 15

member over the upper face of said top and merging into an outer flat flange which follows the contour of the edge of said top and a grid-like member fitted upon said ledge and covering said receptacle.

5 10 3. An improvement in tables as set forth in claim 2 wherein each of said radially arranged arms is provided with a groove extending towards and crossing said inner rim-like member.

4. An improvement in tables as set forth in claim 2 wherein each of said radially arranged arms is provided with a groove extending towards and across said inner rim-like member and said grid cover seated within said rim-like member is formed with grooves registering with the grooves 15 formed in said radially arranged arms.

PETER KAVANAGH.
